UNITED STATES PATENT OFFICE

ARTHUR ROSENBERG, OF BOSTON, MASSACHUSETTS, ASSIGNOR TO A. ROSENBERG & CO., OF BOSTON, MASSACHUSETTS, A COPARTNERSHIP COMPOSED OF ARTHUR ROSENBERG AND PHILIP ROSENBERG

BELT BUCKLE

Application filed December 26, 1929. Serial No. 416,322.

This invention relates to belt buckles and is intended to provide a construction permitting the ready insertion and removal by the wearer of an initial or other ornamental or souvenir sheet without requiring the use of any tools of any kind for loosening the retaining plate or cover which holds the removable sheet in place.

In the accompanying drawings I have illustrated a simple and convenient construction embodying the principles of this invention, in which

Fig. 1 is a longitudinal cross section showing a buckle construction and attached belt illustrating the principles of this invention.

Fig. 2 is a reduced scale front view of such buckle.

Fig. 3 is a rear view of the same.

Fig. 4 is a cross sectional view through the medial line of the buckle.

Fig. 5 is a perspective view of a modified form of cover or sheet retainer.

In the practice of this invention according to the form illustrated in the drawings, I employ any suitable or well known buckle construction which, in this case, comprises a front plate 1, whose middle area is preferably depressed or countersunk to leave a relatively raised border 2. The front plate is provided with lateral flanges 3 which, in the form shown, are provided with inturned ledges 3^a, whose opposite rear ends are formed into a bearing loop 3^b for the reception of bearing gudgeons 4^a projecting from opposite sides of an angle lever 4, which comprises an open bail member 5 for receiving and anchoring the looped or fixed end of the belt 10 forming a permanent anchorage therefor. The short arm 6 of the lever projects outwardly to grip or pinch the tongue or free end 10^a of the belt firmly against the back of the front plate 1 and hold it in whatever position of adjustment may be required for proper service to the wearer.

At its rear end, that is the end adjacent the belt anchorage which is generally positioned toward the left hand side of the wearer, there is provided a hinge connection 9 with a hinged cover 7, whose middle portion subtending the depressed middle area of the

front plate of the buckle is preferably outwardly offset or raised to form, in conjunction with the depressed area of the front plate, a shallow cavity or chamber for the reception of any sheet-like member such as a card, photograph, or initial plate, leaving a relatively offset border 8 lying in close contact with the subtending portion of the front plate.

This border portion 8 is provided at the forward or belt entering end of the buckle with a spring tongue 8^a adapted to overlap and catch against the corresponding end edge of the front plate 1, so that, when the free end of the cover 7 is pressed down tightly against the underlying portion of the front plate, the lip automatically springs into engagement with the edge of the front plate securely holding the cover in position. It is preferred to arrange the spring catch 8^a at the forward or right hand end of the buckle in order to avoid any danger of the free end of the belt releasing the catch as it is pushed through the body of the buckle.

Where it is desired to display an initial or other display plate, the interior portion of the struck-up or offset part of the cover may be cut out to leave merely a raised overlapping portion, as shown at 7^a in Fig. 5. In both cases I prefer that the side edges of the cover should have short overlapping lips or flanges 8^b that serve as frictional gripping and guiding members when the cover is secured in normal position.

As shown most clearly in Figs. 4 and 5 of the drawings, the lateral flanges 3 of the buckle body and the gripping flanges 8^b of the cover are inwardly inclined to leave the front marginal portion of the body overhanging or projecting beyond the inner margins of the flanges. This construction affords such added resistance against the accidental opening of the cover in case the buckle is rubbed against some external object, as the edge of a table or desk, as to eliminate the danger of such accident which would be a serious detriment to the use of such a cover.

What I claim is:

A belt buckle embracing in its construction a front plate provided with inwardly

inclined lateral flanges provided with in-turned ledges forming a fulcral support for a belt-attaching and securing bail, said front plate having its interior portion depressed below the level of its marginal portions to form a shallow pocket, a cover hinged at one end to the front plate and having separate inwardly turned side flanges adapted to engage and grip over the overhanging marginal portions of the front plate, said cover being also provided at its free end with an inwardly projecting lip adapted to engage the adjacent end edge of the front plate.

In witness whereof, I have subscribed the
15 above specification.

ARTHUR ROSENBERG.
